UNITED STATES PATENT OFFICE

135,654

DESIGN FOR A CABINET DOOR

Adolph Marchand, Jackson Heights, N. Y.

Application July 19, 1941, Serial No. 102,286

Term of patent 7 years

To all whom it may concern:

Be it known that I, Adolph Marchand, a citizen of the United States, residing in Jackson Heights, county of Queens, State of New York, have invented a new, original, and ornamental Design for a Cabinet Door, of which the following is a specification, reference being had to the accompanying drawing, forming part thereof.

Figure 1 is a view in front elevation of the cabinet door, showing my new design; and

Figure 2 is a top plan view of the same.

The design comprises a mirror panel bordered by a glass frame, each member of said frame bearing longitudinally arranged spaced lines of small oval-shaped depressions, the area of each frame member between the parallel lines of depressions also being mirrored.

I claim:

The ornamental design for a cabinet door, as shown and described.

ADOLPH MARCHAND.
